OF NEW YORK, N. Y.

RETORT

Application filed June 8, 1923. Serial No. 644,122.

The present invention comprises a retort for treating by a continuous process bituminous coals, shales, lignites and other carbonaceous materials to completely extract 5 hydrocarbon vapors therefrom and produce a maximum quantity of high gravity distillates in a minimum of time and at a minimum fuel and operating cost.

The time required to completely vaporize a 10 given mass of carbonaceous material, at a given temperature, varies directly as the square of the thickness of the mass of material. For quantity production it is important that the mass of material to be treated be 15 spread comparatively thin and uniformly over a heated surface of large area and this is accomplished in the present apparatus.

The application of heat to the metal surface in contact with the carbonaceous material in the present retort is uniform. Independent of any thermostatic control of the 20 retort temperature there is interposed between the surface with which the material is in contact and the heat flame, a heat stabilizing or equalizing material, preferably molten metal, although in some instances metal filings, sand or other material may be used.

In the present retort I arrange to preheat 25 the material which is under treatment while it is being introduced into the retort, but this preheating is intended to heat the material to some point below the vaporizing point in order that volatiles will not be evolved until the material has entered the retort, and has 30 been spread in an even layer. In the present apparatus, after the material has been preheated it is delivered upon a movable, heated support where it is continuously spread out into an even but comparatively thin layer, 35 and after the material has traveled upon the support long enough for the vapors to be evolved it is continuously removed therefrom. Therefore, the preheating, spreading, 40 heating, and discharge all go on continuously but instead of having a body of irregular depth or of varying depth I am able, in the present apparatus, to maintain the material in a uniform layer of shallow depth.

50 Another object is to prevent precipitation

of heavy condensates back upon the material under treatment.

Other objects and advantages will be set forth in the following detailed description of one embodiment of my invention,

55 In the drawings forming part of this application,—

Figure 1 is a vertical sectional view of a retort embodying one form of my invention,

Figure 2 is a sectional view taken on the 60 line A—B of Figure 1,

Figure 3 is a sectional detail view of the agitating or turnover device,

Figure 4 is a detail view showing the valve 65 for controlling the bypassing of heat to the chamber 7.

In the drawings I have shown a retort of bee-hive form, comprising the following essential parts. There is a base or foundation 70 37 on which the fire brick walls 38 of the retort rest. The wall 38 is dome or bee-hive shape, the upper portion 27 being arched and forming the vaporizing chamber 26 in which the vapors are first evolved, and the lower portion forming an enclosure 20 for the source of heat. I prefer to utilize a portion of the product of the retort as a fuel supply although it will be understood that any other kind of fuel such as natural gas, petroleum

75 extracted from wells, or even coal may be used as fuel. In the drawings I have shown a burner 39 which may be supplied with a product of the retort for fuel without intending to exclude the use of other kinds of fuel from the scope of my invention. There is a fuel supply pipe 40 entering through an aperture in the wall 38 and this supplies fuel to the burner 39 which is disposed in the fire box 20 above the floor

80 22 and just below the movable support for the carbonaceous material which is under treatment. Flames issuing from apertures in this burner 39 at many points around the retort act directly upon the bottom or fire plate 12 of the movable support.

85 The movable support or spreading table is preferably revolvable and it is so shown herein and it is also preferably flat in order that the material may be maintained in an even 90 layer. The bottom or fire plate 12 of this 95 100

movable support is here shown as having a central, depending flange 41 which surrounds and is secured to a central, revolvable column 42. There is a sleeve 14^a fitting around the flange 41, and it has radially extending ribs 43 which serve to stiffen and support the fire plate 12 and other parts upon the central column 42. The central column 42 rests on roller bearings 15 which travel on a circular bearing member or track 16 and on its lower end I have shown the column provided with a gear 44. There is a shaft 45 projecting from the exterior of the retort through the walls, and on its inner end it has a pinion 17 which meshes with and operates the gear 44 to revolve the column and the entire movable support or spreading table. This shaft 45 is operated by any power means, and I have shown a pulley 18 which may be driven by a belt from any source.

The central column projects through an aperture 46 in the floor 22 wherein it may revolve freely. Above the fire plate 12 and spaced from the latter I arrange the table or plate 10 on which the material under treatment directly rests. This plate is shown provided with a flange 47 on its outer portion, which engages over and rests upon an upturned flange 48 on the fire plate 12. In the chamber between the plates 12 and 10, which extends over the whole support, I introduce the heat stabilizing or equalizing material. As stated above, various substances may be used for this purpose but lead, which will be maintained in a molten condition by the heat of the burners, is very suitable. I prefer, therefore, to introduce sufficient lead 49 in the chamber to almost fill it and when the burners are in action the molten metal will not only act as a reservoir in storing up heat to be given off uniformly to the product but as it is maintained in a molten condition it will, aided by the rotation of the table, equalize the temperature at all parts of the table.

The table 10 is also secured to the central column 42 so that it revolves with it, and I have shown a metal cap 50 on the top of the column which is covered or enclosed by a cap 14^b of refractory material for a purpose to be referred to hereinafter. The space 26 above the table is for the material under treatment and it is also the vaporizing chamber. The wall 38 forming this chamber is preferably constructed of fire brick, but if it is composed of metal it should be lined with refractory material because it is very desirable that the evolved vapors should not come into contact with any metal while in the vaporizing chamber, as otherwise the vapors tend to condense and to carbonize upon the metal. For this reason I employ the cap 14^b of refractory material on the top of the column. The flue 28 for the passage of the evolved vapors is also made of refractory material such as fire brick, as shown, for sim-

ilar reasons. I have provided a safety valve 29^a in this flue to relieve any dangerous pressure created in the retort.

This flue delivers the vapors into a treating chamber 29. This latter is shown as of double walled construction, the inner wall 51 being spaced from the outer wall 33 to provide an air space 35 at the upper portion in order that the vapors may be reduced in temperature just enough to precipitate certain constituents of the product, such as paraffin wax where hydrocarbons are being distilled from shale. The space between the bottom walls 34 and 30 of this chamber is supplied with a stabilizing material like the table, and for this purpose I prefer to use molten metal such as lead 53.

Within the chamber 29 there are arranged downwardly inclined, baffle plates 32, alternately projecting from opposite side walls of the chamber to provide a tortuous course for the vapors within this chamber and to assist in precipitating certain constituents such as paraffin wax.

The shale or other material to be treated is introduced into the hopper 1 which is provided with a valve or tap 54 to prevent the loss of vapors. From the hopper 1 the material enters the pipe 2 and it then passes into a horizontal pipe 4, where it is fed along to the open end 55 by a screw feed 8. This screw is mounted on a shaft 9 which is driven from the shaft 45 by means of a chain 19 engaging sprockets on these shafts.

The products of combustion pass off through the opening 21, in the wall 38, thence through the annular space 56 surrounding the pipe 4, and thence through the flue 3, the latter enclosing the inlet pipe 2 and forming an annular chamber 57 around it. As these products of combustion travel through the spaces 56, 57—and the flue 3 they heat the material which is being introduced into the retort for treatment but this does not raise the material to a vaporizing temperature.

Part of the products of combustion are bypassed from the space 56 through a port 7 which is controlled by a thermostatic valve 58, and these by-passed products of combustion enter the chamber 59 and serve to heat the lower walls of the chamber 29. From the chamber 59, these products pass through a port 5 and pass out the stack 3 with the others.

The thermostatic valve is shown in Figure 4. It consists of a rod 70 pivoted at the top to the plate 34 and the lower end of this rod is connected at 71 with a lever 72 which pivots from the point 73. At 74 the lever 72 is pivoted to the valve 58 which controls the passage of heat from the space 56 to the chamber 59. When the temperature in the space 59 is raised to the desired degree, the rod 70 is expanded by the heat and the lever 72 is held in the lower position to close the

valve 58. When the chamber 59 cools, the rod 70 shortens and the lever 72 is moved to the dotted line position or some intermediate position which opens the valve 58.

The carbonaceous material delivered from the pipe 4 falls upon the top surface of the spreading table, 10—which in Figure 2 is revolving clockwise, and just behind a spreader 23^a. This spreader consists of a vertically disposed plate, or blade, arranged at an angle to the radius of the table 10, and its bottom edge is spaced from the table according to the depth the material is to be spread upon the table. This blade is stationary, being anchored in the wall of the retort.

At the opposite side of the pipe 4 there is a blade 23, preferably diverging in the opposite direction from the radius of the table to that of the blade 23^a. This blade 23 serves to remove the treated material from the table and therefore its bottom edge 61 is close to or even resting on the top surface of the table.

At one side of but not quite as long as the blade 23, there is a back up blade 23^b the bottom edge of which is preferably spaced from the table surface to correspond approximately with the blade 23^a.

At some point in the path of travel of the material I prefer to provide means for dislodging the particles of material in order to loosen them and to cause all portions to be subjected to heat. For this purpose I have shown a stationary support 25 having arms 63 and 25^a, which carry a pivoted shoe 24. The member 25 is supported at one end from an arm 14 which is connected with the upper wall 27. The latter rests or floats upon the top surface of the table 10 and I have shown it provided with a thin or sharp leading edge 64, followed by a rise 65 and a sudden rear drop 66. As the material travels around with the spreading table it strikes the front edge 64 of the shoe 24 and it rides upon and over the shoe as shown in Figure 3, and this serves to disturb the particles so that all portions are subjected to heat. This shoe, however, does not materially alter the uniform distribution or depth of the material on the spreading table.

It may be assumed that the apparatus is being used to distill hydro-carbon from shale although this is only one of the uses of the present retort. The shale will be supplied to the hopper 1, from whence it moves down the pipe 2 into the pipe 4 where it is fed along by the screw 8 to be discharged at the end of the pipe 4 upon the spreading table behind the blade 23^a. The shale, as above described, is preheated during this travel by the discharging products of combustion. The spreading table 10 is maintained at a temperature considerably higher (at least 200° F.) above the vaporizing temperature (about 760° F.) of the pyro-bitumen educed from the

shale, so that the vapors are not only evolved rapidly but they are cracked to much lighter hydrocarbon compounds than if treated at the normal vaporizing temperature of the pyro-bitumen.

As the material tries to pass the blade 27^a upon the spreading table it is levelled off by this blade to a given depth, determined by the spacing of this blade from the table. It remains in an even layer on the spreading table until it is to be discharged. Rapid vaporization is principally brought about by spreading the material into a relatively thin, uniform layer on the spreading table and subjecting it to a high, uniform heat.

The material is completely treated in one revolution of the spreading table. When it reaches the blade 23 which is close to, or in contact with the table, the spent material is forced over the edge of the table by this blade 23 into a discharge chute 67, which is also provided with a check to prevent the loss of vapors. The blade 23^b prevents the material as it strikes the blade 23 from backsliding upon the table, so that it is forced off the latter.

The arched dome of refractory material converges the evolved vapors to the large outlet 28. The surfaces of the latter as well as all parts within the chamber 26 with which the vapors come into contact are of fire brick or other refractory material to prevent condensation of any heavy hydro-carbon fractions, retaining these as vapors until they enter the first fractionating chamber 29. I have found that at a given temperature the heavy fractions condense more readily upon metallic surfaces than on refractory surfaces and it is important to prevent precipitation of heavy condensates in the rotort upon the material under treatment to avoid clogging and caking and to effect the complete recovery of all condensates at the desired place of recovery.

The chamber 29 is for the condensation of heavy wax or pitch fraction from the hydro-carbon vapors. With paraffin base materials at least this heavy condensate may be largely cracked into light gasoline vapors. The upper portion of the chamber 29 is air cooled to maintain the temperature there at the condensation point of paraffin wax or around 740° F. The bottom is maintained at a temperature say 100° F. higher than the vaporizing temperature. The heavy condensate forms a film on the upper walls of the chamber and on the baffles 32 and this falling upon the bottom 30 is immediately raised in temperature so that part of it is cracked into lighter vapors which pass off through the discharge pipe 36 with the main body of vapors for further fractionation and condensation at lower temperatures. Any fraction which is too heavy to be thus vaporized may be drawn off as liquid through the draw off pipe.

Having described my invention, what I claim is:

1. A retort comprising a revolvable spreading table, means for spreading carbonaceous material in an even layer upon said table, and means for removing the treated material from the table, comprising a blade adjacent to or touching the table to scrape the material therefrom and a blade arranged in advance of said first mentioned blade, said second blade being spaced from the table to permit the layer of material to pass thereunder adjacent to said first blade in the path of travel of the material but acting to prevent the material backing up when acted upon by the removing blade, and means for heating said table to evolve the vapors from the material thereon.
2. A retort comprising a movable spreading table on which carbonaceous material is adapted to be spread, said table comprising spaced members forming a chamber, heat equalizing material in said chamber, means for heating said table, and means for spreading an even layer of carbonaceous material upon said table.
3. A retort comprising a movable spreading table on which carbonaceous material is adapted to be spread, said table comprising spaced members forming a chamber, a layer of low melting point metal in said chamber, means for heating said table and maintaining said metal in molten state, and means for spreading an even layer of carbonaceous material upon said table.
4. A retort comprising a revolving spreading table and means for heating it, means for spreading a layer of carbonaceous material upon said table for treatment, means for removing the treated material from the table, and means interposed in the path of the material on said table, over which the material is caused to pass for the purpose set forth.
5. A retort comprising a flat, horizontal, revolvable spreading table having a chamber therein, a body of metal of low fusing point in said chamber, means for spreading on said table an even layer of carbonaceous material while the table is revolving, means for removing the treated material while the table is revolving, and means for heating said table.

Signed at the city, county, and State of New York, this 2nd day of June, nineteen hundred and twenty-three (1923).

JAMES N. VANDEGRIFT.
